UNITED STATES PATENT OFFICE.

GEORGE MARSHALL, OF WAUPUN, WISCONSIN, ASSIGNOR TO PARAMOUNT KNITTING COMPANY, OF CHICAGO, ILLINOIS, A CORPORATION OF ILLINOIS.

SINGEING-MACHINE.

1,205,099.

Specification of Letters Patent.

Patented Nov. 14, 1916.

Application filed September 22, 1913. Serial No. 790,996.

To all whom it may concern:

Be it known that I, GEORGE MARSHALL, citizen of the United States, and residing at Waupun, county of Fond du Lac, State of Wisconsin, have invented an Improvement in Singeing-Machines, of which the following description, in connection with the accompanying drawing, is a specification, like characters on the drawing representing like 10 parts.

This invention relates to improvements in singeing machines, and more particularly to machines for singeing hosiery of the type which comprises supporting forms which 15 travel in a fixed path through the field of a singeing device, the stockings being placed upon the form prior to its entrance into the field of the singeing device. In this type of machines means have also been provided for 20 removing the stocking from the supporting form after it has been singed.

The invention is more particularly concerned with machines of the socalled "Hagar" type such as illustrated and described in United States Patent No. 971,427, granted September 27, 1910. In such machines the supporting forms are made to conform substantially to the segments of a cylinder, these segments being supported 25 upon brackets extending from the ends of radial arms carried by a rotating shaft. The singeing means comprise gas jets arranged in the superstructure of the machine in such a manner that one jet is adapted to 30 play upon the under side of the stocking upon the form, and the other jet is caused to play down upon the outer surface of the stocking carried by the form.

In these devices the stocking or other 35 article being singed is removed from the support by a traveling stripper, which is caused to follow a path substantially concentric with the path of the supports during a portion of their rotation, the stripper being driven at a speed in excess of that of the support.

One of the objects of my invention is so to construct the singeing machine that the action of the singeing means, whether heat- 40 ers, burners, or jets, will be uniform upon both sides of the support for the article to be singed, a result which it is exceedingly difficult to secure when gas flames are projected upon the upper and under surfaces

of the article being singed, because of the 55 tendency of both flames to ascend.

To attain this result, this invention contemplates arranging the support for the article to be singed in such a manner that its broader faces shall be in planes normal to 60 its axis of rotation, and the heating devices, burners or flames arranged preferably vertically, but in any event adjacent to and parallel with the faces of the supporting forms. By this arrangement it is found in 65 practice that a great saving of gas is accomplished, it requiring substantially one half the amount of gas to operate a machine made in accordance with this invention that it would to operate a machine of the character 70 above described.

A further advantage accomplished in a machine made in accordance with this invention is that by reason of the smallness of 75 the flame required, and its location, the operator's face is not in danger of being burned.

Another object of this invention is to provide a stripper which will embrace or partially surround the form during a portion 80 of its rotation, and by traveling at a greater speed than that of said form, engage the singed article on both sides of the form, thereby stripping it from the form by even pressure on both sides and avoiding stretching or mutilation of the article.

Other objects of my invention will be apparent from the following description and drawings, and will be pointed out in the appended claims. It is to be understood, however, that the drawing illustrates one of the 90 preferred embodiments of my invention, but that it is not restrictive and that my invention comprises any means whereby the singeing burners are adapted to project flames equally from oppositely disposed burners 95 upon a traveling support for the article to be singed in such a manner that the jets of flame will impinge thereupon at equal angles to the vertical.

In the drawings, Figure 1 is a side elevation of a singeing machine embodying my invention; Fig. 2 is a plan view thereof; Fig. 3 is a detail view of a portion of one of the supports shown as having two vertical hydro-carbon burners, and Fig. 4 is a 105 detail section through a support and the stripper carrier, and showing the form of stripper.

In the drawings 1 represents the frame which may be of any construction suitable to support the operative parts of the machine.

5 2 is a main shaft journaled in the bearings 3 upon the main frame, and supports a spider 4 which is provided with a series of radial arms 5, which carry the supporting forms for the article to be singed. Each 10 radial arm 5 is provided at its extremity with a bracket 6 which is secured thereto by suitable bolts, and is provided with an offset portion 7 which is attached at its outer end to the supporting forms 8 for 15 the article to be singed.

The offset portion above described is provided in order that the article on the support may pass readily and freely between the burners, and also in order to provide 20 room for the stripping mechanism, which will be hereafter described. The supporting form or supports for the article comprise preferably thin arcuate members having relatively greater breadth, the broad faces being in substantially vertical planes, so that the article when placed upon the form will be stretched or held with its greater width in substantially radial relation to the axis of rotation.

30 As illustrated in Fig. 1 the arcuate supporting members lie in segments of the periphery of the circle described by the ends of the radial arms. By reason of this construction the articles are passed between the singeing flames in the direction of their length and are stretched upon the supports so that the flames play upon relatively narrow transverse surfaces. By reason of this construction a relatively short burner 12 35 may be utilized and a more uniform singeing of the articles produced by reason of the fact that the heat of the flame can be distributed with almost exact uniformity throughout the width of the support; whereas in devices heretofore constructed, in 40 which the supports are segments of a cylinder, the heating of the burners upon the under side is much greater than those upon the upper side of the support; and in 45 devices in which the supports are arranged upon vertical or radial arms the long burner required causes a greater amount of heat to be applied to the upper end of the article than at the lower end by reason of 50 levitation caused by the successive jets.

Mounted upon the main frame 1 is a superstructure 9 which carries at its upper end a gas pipe or other fuel supply 10, which may be mounted in any suitable 55 port. Depending from the fuel supply 10 is a T joint 11, which connects with preferably vertically arranged burners 12, 13, located on opposite sides of the path in which the support for the article to be singed 60 travels. Each of the burners 12, 13, is pro-

vided with a series of openings or jets which are adapted to direct the flames toward the path in which the form 8 travels.

In view of the fact that burning gas has a strong tendency to rise, it is obvious that 70 if equal jets are projected at intervals along each burner, a greater heat will be supplied toward the top or upper end of the burner than near the bottom thereof. In order to obviate this difficulty the burner may be 75 provided with orifices, the larger holes being near the bottom and decreasing in diameter toward the upper end of the burner. By properly regulating the size of such orifices, an even distribution of the flame may be had 80 over the entire surface, especially where as in the device disclosed herein the areas acted upon by the flames are relatively narrow.

Rotation is imparted to the shaft 2 which carries the traveling supports through a 85 gear 14, which is rigidly attached to the shaft, and which meshes with a gear 15 mounted upon a drive shaft 16 which is journaled in suitable bearings 17, 18, on the frame. The shaft 16 is provided with the 90 usual fast and loose pulleys 19 and 20.

In order to provide for the removal of the singed article from the form a stripping mechanism is provided which comprises an endless stripper carrier, preferably an endless chain 21, which passes around a suitable sprocket gear 22 rotatably mounted upon the shaft 2, thence over a pulley 23 located preferably near the top of the machine and journaled in supports carried by 100 the superstructure 9, thence through a guide 24, which is in the form of the arc of a circle and which extends from near the top of the machine to a point somewhat below the medial portion thereof. At the termination 105 of the guide the stripper carrier passes over a pulley 25 which is suitably journaled in a bearing 26 carried by the members of the frame 1. The stripper carrier thence continues to the point first mentioned. The stripper carrier is provided with a stripper 27 which is mounted upon the carrier chain 21. The stripper 27 comprises a shank portion 28 terminating in a U-shaped frame 29 which is adapted to extend around and embrace the broad sides of the support 8, and thereby engage the singed article upon both sides in such a manner that the same will be thrust off of its support without unduly 110 distorting or tearing the same. In order to assure a close contact between the stripper and the support which carries the singed article the U-shaped portion 29 of the stripper is provided with an elastic facing 30, preferably of rubber, which is adapted to 115 press gently but firmly against the sides and edge of the support as the stripper is forced along the same.

In order that the stripper may force the singed article from its support, it is neces- 120

sary that the stripper shall travel in a path parallel with the path of said support, and at a greater relative speed. To effect this result suitable gearing 20 is provided connecting the driving shaft with the sprocket which drives the stripper carrier. This train of gearing comprises a large gear 31 mounted upon the driving shaft 16 which is adapted to mesh with a smaller gear 32 rotatably mounted upon the main shaft 2 and connected with the sprocket wheel 22 which serves to drive the carrier chain 21.

In the operation of this device the operator stands at the left of the machine, as illustrated in Fig. 1, and applies a stocking or other article to the form as the free end of the same ascends. The article when placed upon the form is so spread out that substantially the entire article is displayed as two parallel faces. Upon the further movement of the support, the article is carried between the burners 12, 13 and flames of equal strength are projected from said burners against the faces thus exposed. This serves to carbonize or burn off the undesirable fibers which project from the article. The singeing operation having been effected the article is discharged from its support by the stripper 27. This stripper, as before stated, is secured to the stripper carrier 21 which moves in a path concentric with the path of the supports for the article operated upon. The stripper is, as before stated, driven at a higher speed than that imparted to the carrier, and therefore serves to traverse the support during a portion of the rotation of the latter. The operation of the stripper is so timed that it will engage and embrace the support in advance of the bracket 7 which supports the latter, and will pass beyond the end of the support and discharge the article therefrom about the time the free end of the support 8 reaches the horizontal plane of the axis of the machine.

It is to be understood that my invention thus described is merely illustrative, and that the invention herein disclosed and described is applicable to other forms of traveling carrier, and that the burners may be located in other positions than that shown within the scope of my invention, and that other means may be provided for supporting and actuating the stripper in accordance with the character of the particular machine to which the same is to be applied.

While the burners may be otherwise located than in the vertical and parallel arrangement illustrated and the advantages of the invention in its broader aspects still be secured, yet with the Hagar type of machine referred to this location is preferable. The operator may thus stand at one side of the machine and readily and easily place the stockings on the machine as the forms ascend in their travel in front of him;

stockings may thus be removed by the stripper without injury and discharged at the opposite side of the machine where they will not interfere with the feeding of the machine; and the burners supplying equal amounts of gas will singe the stockings equally on both sides, the action of gravity and the air currents affecting both burners equally and causing the flames to rise naturally from both burners thus securing the singeing with the minimum amount of heat and without danger or discomfort to the operator.

Having fully described my invention, what I claim as new and desire to secure by Letters Patent is:

1. In a singeing machine, a traveling support for the article to be singed having its broader face in vertical planes normal to its axis of rotation, means for advancing the same in the direction of its length, singeing means comprising substantially equal hydro-carbon burners located on opposite sides of the path of said traveling support and adapted to project jets of flame thereon at substantially equal angles to the vertical whereby the articles will be singed uniformly throughout their length.

2. In a singeing machine, a traveling support for the article to be singed having its broader face in vertical planes normal to its axis of rotation, means for advancing the same in the direction of its length, singeing means comprising substantially equal hydro-carbon burners located on opposite sides of the path of said traveling support and adapted to project graduated jets of flame thereon at substantially equal angles to the vertical, whereby the articles will be singed uniformly throughout their length.

3. In a singeing machine comprising a traveling support for the articles to be singed having its broader face in vertical planes normal to its axis of rotation and means for actuating the same, singeing mechanism comprising a plurality of extended hydro-carbon-burners, having graduated orifices arranged in substantially vertical planes parallel to the planes through which the respective sides of the support travel and spaced equally therefrom, whereby the articles will be singed uniformly throughout their width and length.

4. In a singeing machine comprising a traveling support for the articles to be singed having its broader face in vertical planes normal to its axis of rotation and means for advancing the same in the direction of its length, singeing mechanism comprising a plurality of extended hydro-carbon burners having graduated flame jets arranged in substantially vertical planes parallel to the planes through which the respective sides of the support travel and spaced equally therefrom, whereby the articles will be singed uniformly throughout their width and length.

4
cles will be singed uniformly throughout their length and width.

5. In a singeing machine having singeing means, an arcuate support for the articles to be singed having its broader faces in substantially vertical planes mounted for rotation in a circular path in the direction of its length, and means for rotating the same, a resilient stripping device adapted to embrace said support during a portion of its travel and engage the articles carried thereby, and means for driving the stripper at a relatively greater speed than that of said support.

10 6. In a singeing machine having singeing means, an arcuate support for the articles to be singed mounted for rotation in a circular path and means for rotating the same, a stripping device comprising a U-shaped member adapted to embrace said support during a portion of its travel and engage the articles carried thereby, and means for driving the stripper at a relatively greater speed than that of said support.

20 7. In a singeing machine having singeing means, an arcuate support for the articles to be singed mounted for rotation in a circular path and means for rotating the same,

a stripping device comprising a U-shaped member having a resilient face adapted to 30 embrace said support during a portion of its travel and engage the articles carried thereby, and means for driving the stripper at a relatively greater speed than that of said support.

35

8. A singeing machine comprising a plurality of thin wide supports for articles to be singed mounted for rotation in a circular path with the wide faces traveling in vertical planes normal to the axis of rotation, 40 means for stripping the singed articles from the supports located at the side of the machine opposite to that at which the operator stands in placing the article to be singed on the supports, and means located substantially midway between said sides for singeing the articles equally on both sides by the burning of equal amounts of gas.

In testimony whereof, I have signed my name to this specification, in the presence 50 of two subscribing witnesses.

GEORGE MARSHALL.

Correction in Letters Patent No. 1,205,099.

It is hereby certified that in Letters Patent No. 1,205,099, granted November 14, 1916, upon the application of George Marshall, of Waupun, Wisconsin, for an improvement in "Singeing-Machines," an error appears in the printed specification requiring correction as follows: Page 4, line 39, claim 8, after the word "path" insert the words *in the direction of their length*; and that the said Letters Patent should be read with this correction therein that the same may conform to the record of the case in the Patent Office.

Signed and sealed this 19th day of December, A. D., 1916.

[SEAL.]

R. F. WHITEHEAD,
Acting Commissioner of Patents.
